APPARATUS FOR AMPLIFYING ELECTRIC OSCILLATIONS

Original application filed January 9, 1925, Serial No. 1,471. Divided and this application filed March 24, 1930. Serial No. 438,591.

This invention relates to apparatus for amplifying electric oscillations and particularly to systems which are made up of a number of stages of cascaded audion amplifiers.

It is a well-known experimental fact that when audion amplifying stages which give a relatively high voltage amplification per stage are connected in cascade, the overall voltage amplification of the cascaded system is not equal to the product of the amplification factors of the several stages. This failure to secure the theoretical voltage amplification from a plurality of stages is particularly pronounced at the higher frequencies from 500 to 1500 kilocycles per second but is marked at the "intermediate frequencies" lying between 30 and 100 kilocycles. If the amplifying tubes in a number, n , of like cascaded stages were employed with full efficiency, the overall voltage amplification of the system would be numerically equal to the voltage amplification per stage raised to the n th power. This I define as true cascade amplification. The amplification obtainable with prior systems and radio receivers has fallen far short of such a figure. With a radio-frequency transformer-coupled amplifier, assembled in the usual fashion and with the tendency towards self-oscillation in individual stages controlled by the introduction of variable losses in the input stage, I have found, experimentally, a voltage amplification of 100 for a single stage, 200 for two similar stages in cascade and 310 for three similar stages in cascade. In another typical cascade system of the "intermediate frequency" type, operating at a frequency of 30 kilocycles, the voltage amplification for one stage is of the order of 30, for two stages 450, and for three stages 900. If the amplification for one stage is termed A , the amplification observed at the higher frequencies corresponds respectively, to A^1 , $A^{1.15}$ and $A^{1.24}$ for one, two and three stages; and the amplification at intermediate frequencies was A^1 , $A^{1.82}$ and $A^{2.0}$, respectively, for one, two and three stages. The significance of these figures is not in the absolute values of the amplification, which vary with the types of tubes and coupling

units employed, but in the absence of a true cascade effect in the overall amplification of a plurality of stages. Quantitative experiments indicate the absence of this cascade effect in all ordinary amplifiers, irrespective of the type of audion tube employed.

An object of the present invention is to provide amplifying apparatus comprising a plurality of cascaded stages and in which the overall amplification increases exponentially with the number of stages. A further object of the invention is to provide a plurality of tuned amplifying stages which are so constructed and arranged that the input reactance of each amplifying stage is independent of the value of the variable reactance in the input circuit of the succeeding stage. A further object is to provide a selective radio receiver having a plurality of tuned amplifying stages adjustable to a common resonance frequency by the manipulation of a single tuning control. More specifically, objects of the invention are to provide certain details of construction and combinations of amplifying stages or portions thereof which are hereinafter described and claimed.

Contrary to the universal opinion, based upon evidence similar to that presented above in quantitative form, that the voltage amplification of each added radio frequency stage is progressively smaller and that no real advantage is gained by using more than two, or at most three, stages of amplification, I have demonstrated that a number of stages may be so cascaded as to provide an overall voltage amplification which increases exponentially with the number of stages.

To secure this cascade amplification, I have found two definite conditions which must be fulfilled: first, each stage must be a true one-way repeater; second, the interaction between non-adjacent stages due to stray electric and magnetic couplings and to small voltage drops in common battery leads, must be reduced to insignificance. In other words, if each stage is so arranged and adjusted that the input circuit of any given audion repeater has no appreciable effect upon any circuit ahead of this input circuit in the amplifier,

and if the current in this input circuit affects all circuits beyond it in the cascade amplifier only through the agency of thermionic space currents in the audion of this stage, then the amplification given by a number of stages 5 will be numerically substantially equal to the amplification of one stage raised to a power equal to the number of stages.

I have also discovered that the maintenance 10 of a true one-way action in each of a series of stages is beneficial in a different way: it renders the effective input reactance of any given stage independent of the constants of each of the succeeding stages, including the 15 output circuit of the particular stage in question, with the result that when the coupling units of each include a tuned circuit, the tuned circuits of all the stages can be made mutually resonant by means of reactances external 20 to the several audions which are all equal. In previous attempts to tune a plurality of similar stages by a single control the progressive differences which may exist in the input reactances of a series of cascaded stages, 25 which differences are present even though the external tuning reactances are equal for all the stages, has apparently been overlooked, with the result that the bend of frequencies through which the different stages 30 are even approximately in resonance with each other is extremely limited.

I also gain increased selectivity in a series 35 of cascaded stages owing to the fact that the variation of effective input capacity with frequency which is known to exist when the output circuit of an amplifying stage is allowed to react upon the input circuit of that stage, is absent in an amplifier made up of one-way stages.

40 For a better understanding of my invention, reference is had to the accompanying drawings, in which,

Fig. 1 is a diagram showing the schematic organization of my invention.

45 Fig. 2 is a circuit diagram of a one way amplifying stage suitable for use with my invention.

Fig. 3 is a broken perspective view of one 50 physical embodiment of a plurality of cascaded one-way stages, and

Fig. 4 is a circuit diagram of a radio receiver including a plurality of cascaded one-way radio frequency amplifying stages, the first or input amplifying stage being adapted 55 for use with an antenna or capacity collecting structure.

In the schematic diagram of Fig. 1 an amplifying system according to my invention is shown embodied in a radio receiver in which 60 the antenna-ground circuit 1, 2, works into a cascaded series of unidirectional amplifying stages 3, 4, 5 and 6, which work in turn into a detector stage 7.

True unidirectional action of the cascaded 65 stages such as is contemplated in the present

invention is not obtained simply by the neutralization of the grid-plate capacity of each tube and the usual shielding of the stages from each other. As is described in the co-pending application of Stuart Ballantine, 70 Ser. No. 720,708, filed June 17, 1924, an audion amplifying stage of ordinary type will usually not be unidirectional for several reasons, as follows:

1. On account of the electrostatic coupling 75 due to the capacity between grid and plate electrodes of the audion and their connections;

2. On account of the flow of ions or electrons from the filament to the grid of the 80 audion;

3. On account of the coupling due to the flow of the plate (thermionic) current through the filament;

4. On account of the charge induced upon 85 the grid electrode by the varying space charge;

5. On account of any incidental coupling 90 between the coils or condensers and their connections on either side of the repeater tube. 95

For purposes of discussion, I shall separate all amplifying stages into two general classes, which I define as follows:

First, one-way stages, in which retroactive and interactive couplings due to all five of the 95 above-named causes have been substantially eliminated; second, neutralized stages, in which the coupling of the first type only (electrostatic capacity between grid and plate) has been eliminated. When two neutralized stages are cascaded, if the losses in the interstage coupling transformers are sufficiently high, the combination may be non-oscillatory over a substantial range of frequencies. But when two or more one-way 100 stages are cascaded, not only is the combination non-oscillatory, regardless of the nature of the couplings used, but true cascade amplification results. The failure of conventional amplifiers comprising two neutralized 105 stages so proportioned as to be non-oscillatory, to eliminate all important retroactive couplings accounts for the relatively high overall amplification in such systems. Although the residual regeneration present in 110 two neutralized stages may produce an overall amplification for these two which is greater than that which would be obtained if the same two stages were converted to the one-way type, the significant fact is that not even an 115 approximation of true cascade amplification is obtained when more stages are added to the neutralized amplifier.

A typical one-way amplifying stage is shown diagrammatically in Fig. 2. The input transformer L_1 , L_2 is tuned by a condenser C_2 in the usual manner. The audion T comprises a three electrode amplifying tube having capacity C_m between the grid and plate P . The output circuit of the stage includes the 120 125 130

primary L_4 of the transformer L_4 , L_5 , the secondary of which is tuned by the condenser C_3 , these forming the input circuit of the succeeding stage. The input terminals of the stage, i. e., of L_2 , C_2 , are not connected across the input terminals of the audion T , but the low point, Y , of the secondary of the input transformer is connected to a filament lead F through a coil L_6 , which is coupled to L_4 , and a grid biasing battery C . By low-point of a circuit element or impedance I mean that point of the element which is at the lowest alternating current potential, or, in an audion circuit, most closely approaches the alternating current potential of the audion filament. The A and B batteries and the rheostat R may be of the usual forms.

As has been described in the above-mentioned Ballantine application, this arrangement of input and output networks constitutes a bridge having the capacity arm C_m and a second capacity arm C_e between the grid and filament terminals which second arm may comprise the capacity between the electrodes or their connecting wires, or an external condenser. The points G , P and F , are three corners of the bridge system and the fourth point is the point X in the output inductance L_4 . Due to the coupling between L_6 and L_4 , the point Y in the input circuit is at the same A. C. voltage as some point X of the output circuit, and the input of the stage is effectively across G and X , which are at opposite corners of the bridge. By adjusting C_e to provide the proper capacity and thus balancing the bridge, the reaction of the output upon the input circuit through C_m is prevented since the output is across P and F , the other corners of the bridge. Theoretically the bridge can be balanced independent of frequency with any value of coupling between the coils L_6 and L_4 since a decrease in this coupling, with a given pair of coils, is entirely compensated in obtaining a balance by an increase in the value of capacity C_e . I have found in one specific practical embodiment of my invention using this type of circuit with an audion of the type known commercially as UV-201A that a suitable value for the coefficient of coupling between coils L_6 and L_4 is $K=0.25$, where K is defined by the relation:

$$K = \frac{M_{46}}{\sqrt{L_4 L_6}}$$

The numerical ratio between inductances L_6 and L_4 should be in this case $L_4/L_6=4$ to 4.5. A bridge balance may be obtained with a capacity at C_e of the order of 40 micro-microfarads. If this balance is obtained in the absence of thermionic space currents within the audion, then the electrostatic coupling through C_m only is eliminated and the stage falls in the class of neutralized stages. My

invention is not, of course, limited to these or any other specific constants.

In order to develop this system further, into a one-way stage, the other causes of retroactive currents are eliminated as follows:

The grid-filament current, which manifests itself as a resistance shunted across C_e is eliminated by a C battery or other means for biasing the grid negatively. If a C battery is not used, the effect of the grid-filament current may be compensated by the use of extra balancing resistances in the bridge arms as explained in the Ballantine application. The coupling arising from the flow of plate (thermionic) current in the filament is eliminated by the use of a high-capacity filament by-pass condenser C_1 , shunted across the filament terminals. Incidental couplings between the input and output circuits are eliminated by shielding around the coils, condensers, and high-potential connecting wires.

The general technique of radio and audio-frequency shielding is well-known in the art, as is the practice of shielding certain parts of amplifiers from each other. I have found, however, certain special types and arrangements of shields to be peculiarly adapted for the provision of one-way action in cascade amplifier circuits. An individual shield for each transformer and its associated leads is absolutely essential for one-way action. It is also desirable to shield the tuning condensers from each other and from the audions and associated parts. The preferred form of shielding is indicated diagrammatically by dotted lines in Fig. 2, which lines define four enclosed spaces S_1 , S_2 , S_3 and S_4 , within which are located, respectively, the input transformer L_1 , L_2 , input tuning condenser C_2 , the output transformer L_4 , L_5 , which comprises the input transformer of the succeeding stage, and the tuning condenser C_3 for tuning L_5 .

These shields may be formed of highly conducting metal, of a thickness which depends upon the constants of the metal. With coupling transformers having straight solenoidal windings, positioned about 5 inches between centers, sheet copper or sheet brass about 0.02 inches thick is suitable.

A practical physical embodiment of the principal parts of a stage and of the shields is illustrated in Fig. 3, in which view the several parts are identified by the same reference characters as are used in the diagram of Fig. 2. The several shields S_1 , S_2 , S_3 and S_4 , take the form of closed rectangular boxes or cubicles within which the elements are placed.

In Fig. 3, the input stage is shown at the right of the first complete amplifying stage, it being understood that additional and similarly constructed amplifying stages will ordinarily be arranged to the left of these stages. The particular arrangement illus-

trated is intended for use in a cabinet of the usual type and with the aligned ends of the boxes adjacent the usual vertical panel. The fixed inductances are arranged at the lower part of the assembly, the several cylindrical transformers being arranged with their axes horizontal and normal to the ends of the shields S_1 , S_3 , which will be adjacent the panel. The shields S_2 , S_4 , which house the tuning condensers C_2 , C_3 are shorter than the boxes S_1 , S_3 , and are arranged above the latter at their forward ends. The socket for audion T , the battery leads and the condensers C_1 , C_e , are positioned on or above the shelf which is provided by the rear portion of the shield boxes S_2 , S_4 , it being obvious that these various parts are insulated from the shields. An additional shield S_5 is provided, this taking the form of a flat plate which is positioned above and parallel to the upper surfaces of the shields S_2 , S_4 , and which has spaced openings above the several tube sockets.

The second of the two requirements for cascade amplification, viz: isolation of the several stages, is accomplished with respect to parasitic couplings by the shields which surround the coupling units, since these shields serve to isolate the units individually. With certain arrangements, I have found it advisable also to enclose the audion tubes in individual shields S_6 . In addition to this, it is necessary to bring to ground potential all low voltage battery leads by the liberal use of high-capacity by-pass condensers.

It will be noted that the tuning condensers C_2 and C_3 are shielded from their respective inductances, L_2 and L_3 , and that the wiring within a stage is positioned within the shields which house the parts of the stage. The tube socket and battery wires are located outside of the boxes but the leads from the plate and grid terminals of the socket pass directly into the boxes S_2 , S_4 , and the exposed portions of these leads are kept as short as is possible.

I have enumerated all of the features necessary to provide one-way characteristics for the amplifying stage of Figs. 2 and 3 except that one which concerns the retroactive coupling due to the space charge in the audion. As pointed out in the copending Ballantine application, Ser. No. 720,708, the electric flux due to this mobile space charge which constitutes the thermionic plate current of the audion, manifests itself as a change in the effective grid-plate capacity of the audion. When the filament of the audion is heated and the steady plate voltage turned on the effective capacity between grid and plate is different from the electrostatic capacity between these electrodes. I wish to emphasize that this is no minor, second-order effect.

In an ordinary receiving audion, I have de-

tected a change in the effective grid plate capacity when the filament was turned on, which amounted to 50% of the original electrostatic capacity between electrodes.

Thus the old methods of securing a balance with a cold filament give spurious results, and do not produce the desired one-way effect even though the circuit purported to be balanced includes all physical elements necessary for securing an accurate balance. An accurate balance can be secured only when due consideration is given to the effects of this space charge. I obtain a true one-way action by adjusting the circuit constants to provide a bridge balance on each individual stage with the filaments lighted and with the normal thermionic space current flowing, suitable apparatus for and the method of securing a "hot tube" balance being described by me in QST, August, 1924, pages 32 to 34.

The physical arrangement of an amplifier having more than two cascaded stages will be apparent from a consideration of Fig. 3, and Fig. 4 is a circuit diagram of an amplifier, specifically a radio receiver, having three stages in addition to the first amplifying or input stage, and the audion detector. The several tubes of the four amplifying stages are indicated by numerals 1 to 4, respectively, and the detector audion by numeral 5. The input or first amplifying stage differs from the succeeding stages as the reactance of the first input transformer will be influenced by the properties of the collecting structure with which the receiver is associated. In addition to the input transformer L_1 , L_2 , and tuning condenser C_2 , an adjustable reactor, as the condenser C_a is provided in series with inductance L_1 , the antenna A and ground G being connected across C_a , L_1 . The input and output networks associated with the subsequent amplifying audions are identical, and are constructed and arranged as described in detail in connection with Figs. 2 and 3. In cascading a plurality of stages, common batteries are used, and additional by-pass condensers of large capacity C_B and C_C are provided across the B and C batteries, respectively. Separate by-pass condensers C_1 are provided for each stage and individual balancing condensers C_e are of course necessary, the condensers C_e being once adjusted and preferably clamped in proper position to balance the separate stages.

The several tuning condensers C_2 are arranged for operation by a single control, which as indicated in Fig. 3, comprises a shaft arranged parallel to the front of the set, suitable insulation being provided between the sections of the shaft to which the several sets of movable plates are attached. Due to the fact that the effective input reactances of stages between terminals G and Y , note Fig. 2, are equal when the coupling trans-

formers have primary and secondary inductances, respectively, equal to each other, the one-way stages including audions 2, 3 and 4 may be simultaneously tuned to resonance by similar variable condensers C_2 , which are so coupled as to move in unison. Although the effective input reactance of the input audion 1 is affected by the particular current collecting structure which may be used, the effect of the arbitrary value of such a structure can be eliminated by a suitable adjustment of the compensating condenser C_a . As the input stage is also a one-way repeater, the adjustment of C_a is substantially independent of frequency and in actual practice no variation in the setting of C_a can be observed when the latter is adjusted, for a given antenna, for best reception of the highest or the lowest frequencies within the broadcast range. The four amplifying stages may be concomitantly tuned to resonance by a single control, even though the tuning of the individual stages be extremely sharp, an operation which has not been possible with previous constructions which include a plurality of sharply tuned amplifying stages. In prior constructions using a single control, no account has been taken of the fact that even though the constants of all external reactances are equal, a progressive difference may exist between the effective input reactance of each amplifying tube, with the result that there has been only one or two settings of the single control at which all stages were on the resonance peak. At other settings or frequencies all but one of the stages have been slightly off the resonance peak. The present invention avoids this difficulty since the input stage and all subsequent stages will be tuned to the resonance peak when the stages are one-way amplifiers and the external reactances of the several stages are identical.

In its broader aspects, the present invention comprises the cascading of a plurality of one-way repeaters. Contrary to previously accepted theories, I have found that the elimination of such incidental feed-back as has increased the amplification in one or two stages, has not resulted in lessened amplification for a plurality of stages but has had the surprising result of securing an actual amplification equal to the maximum which was theoretically obtainable with a given number of similar stages. I have built cascaded amplifiers having four resonant one-way stages operating at frequencies between 500 and 1500 kc. in which each stage was constructed and adjusted in accordance with my invention as described herein. The amplification for a single stage was 7, and the observed overall amplification of the four stages was, within the limits of experimental error, equal to 7⁴ or 2401.

It is apparent that the invention is not limited to the specific circuit details and ar-

rangements since other means are now known or may be devised for eliminating some of the causes of retroaction in a stage or between stages.

This application is a division of my copending application Ser. No. 1,471, filed Jan. 9, 1925.

I claim:

1. A radio frequency amplifier comprising a plurality of cascaded vacuum tube stages of the type including means suppressing the effects of capacitive coupling between control grid and plate, characterized by the fact that condenser-tuned transformers interlink said stages, and individual shields are provided for each transformer, for each condenser and for each vacuum tube. 75

2. An electrical amplifier for radio frequency oscillations comprising a plurality of cascaded vacuum tube amplifier stages linked by condenser-tuned transformers, a circuit associated with each stage to neutralize undesirable coupling between the output and input circuits thereof, and individual shields for said tuning condensers, for each of said transformers, and for each vacuum tube. 85

3. An electrical amplifier stage comprising in combination a vacuum tube provided with plate, grid, and filament electrodes, an input and an output transformer, a circuit associated with said stage to neutralize undesirable coupling between the output and input circuits thereof and capable of adjustment under operating conditions, means for overcoming undesirable effects of electron flow from filament to grid, a by-pass condenser for said filament, and individual shields for each of said transformers and for said vacuum tube, the elements of said combination being so associated and adjusted that the amplifier stage is unidirectional in action. 100

4. An audion amplifier system comprising a plurality of audion amplifier stages disposed in series in cascaded arrangement; each of said amplifier stages being constructed and arranged for one-way forward action only, and comprising, in combination, means for reducing the effect of retroactive currents due to capacity between the control element and anode of the audion tube, means for imparting a negative potential to the control element with relation to the cathode in order to reduce the flow of electrons to the control element, means for reducing the effects of the charge induced upon the control element by the presence of space charge existing within the audion when the cathode is in emitting condition, and means for shielding the stage to substantially prevent coupling external thereto not desired for the forward action thereof; whereby said audion amplifier system is caused to operate with approximately true cascade amplification, substantially in the manner described. 115

5. An audion amplifier system comprising 130

a plurality of audion amplifier stages disposed in series in cascaded arrangement; each of said amplifier stages being constructed and arranged for one-way forward action only, and comprising, in combination, means 5 for reducing the effect of retroactive currents due to capacity between the control element and anode of the audion tube, means for imparting a negative potential to the control element with relation to the cathode in order 10 to reduce the flow of electrons to the control element, means rendering the direct current potential between said control element and cathode substantially independent of the flow of spaced current through said cathode, and means for shielding the stage to substantially 15 prevent coupling external thereto not desired for the forward action thereof; whereby said audion amplifier system is caused to operate with approximately true 20 cascade amplification, substantially in the manner described.

6. An audion amplifier system comprising a plurality of audion amplifier stages disposed in series in cascaded arrangement; each 25 of said amplifier stages being constructed and arranged for substantially one-way forward action only, and including, in combination, an audion tube device and a plurality 30 of impedances forming an alternating current Wheatstone's bridge having two conjugate arms comprising respectively the input circuit of the stage and the output circuit thereof, and four balancing arms characterized 35 by the fact that the product of the impedances of one pair of non-adjacent balancing arms is substantially equal to the product of the impedances of the remaining pair of non-adjacent balancing arms throughout the 40 frequency range of the stage, means for imparting a negative potential to the control element with relation to the cathode in order to reduce the flow of electrons to the control element, means for making the cathode a 45 substantially equipotential surface with regard to alternating currents to be amplified, means for reducing the effects of the charge induced upon the control element by the presence of space charge existing within the audion 50 when the cathode is in emitting condition, and means for shielding the stage to substantially prevent coupling external thereto not desired for the forward action thereof; whereby said audion amplifier system 55 is caused to operate with approximately true cascade amplification, substantially in the manner described.

In testimony whereof, I affix my signature.
LEWIS M. HULL.
